UNITED STATES PATENT OFFICE

2,545,810

GLASS FILLER FAUCET

Ralph J. Fisher, Altadena, Calif.

Application June 17, 1946, Serial No. 677,335

2 Claims. (Cl. 251—116)

1

This invention is an advance in water faucets and especially of the type having a downwardly extending stem device to be engaged and oscillated by pressure of the side of an applied receptacle, such as a water glass.

An object of the invention is to greatly simplify the construction and reduce cost of manufacture of faucets of this type.

A further object of the invention is to provide a single unitary device for packing certain parts and at the same time having the second function of automatically re-seating the movable closure member of the faucet after it has been opened for liquid flow in the faucet, thus eliminating the usual metal spring.

Another object of the invention is to provide a unitary resilient packing member of tubular form to snugly, axially receive a stem element of the faucet and having expanding capacity to effectively draw the valve closure to its seat in the faucet.

The invention resides in certain advancements in this art as set forth in the ensuing disclosure and having, with the above, additional objects and advantages as hereinafter developed, and whose construction, combinations and details of means will be made manifest in the following description of the herewith illustrative embodiment; it being understood that modifications, variations and adaptations may be resorted to within the scope, spirit and principles of the invention as it is more directly claimed in conclusion hereof.

Figure 1 is an axial section of the faucet.

Figure 2 is a side elevation of the valve seat ing packer.

The faucet body includes a downturned spout 2 forwardly of a barrel 3 leading to the spout by way of a lateral passage 4 which is under a cross-wall 5 at the inner end of the supply chamber 6 of the faucet.

Screwed onto the lower end of the barrel 3 is a collar or boot 7 having a shoulder 8 on which rests a gasket ring 9 compressed by the boot against the end surface of the barrel to make a tight seal about an elongate, tubular bearing 10 whose lower end lodges on a shoulder 11 in the boot and by which the upper, reduced or neck end 12 of the bearing 10 is jammed into place in an aperture 5a in the cross-wall 5 and against a packing ring 13 at the said neck 12 to seal the aperture joint.

The upper end of the tubular bearing 10 has radial outflow ports 10a to the passage 4.

The lower end of the boot 7 has a concaved seat

2

1a on which is suspended a flared head 15 of a stiff stem 16 having a cushioning bumper disc 17 on its lower end to be engaged by the side wall of a drinking glass or other receptacle whose 5 sidewise pressure swings the stem off center whilst its head 15 fulcrums on the seat 1a. As the head oscillates it comes into operative contact with the bottom end face of a button 18 fixed on the lower end a spindle 19 which is axially shiftable and guided in the fixed bearing 10 and has fixed on its top end a faucet closing head 20 operative to engage the contiguous corner 21 of an axial bore 10b leading to the bearing ports 10a.

15 A distinctive feature of this invention embodies a single and unitary device having the dual purposes of making a tight seal between the sliding spindle and its guiding bearing 10 and of constituting the means for effectively moving the valve closure 20 to its seat 21 to close the faucet.

20 As here shown the spindle head closing means consists of an elongate and firm tube 25 of rubber or its equivalent (for its purpose) which is materially compressed between the button 18 of the spindle and the end shoulder 26' of a pocket 26 in the bearing 10 and which pocket is sufficiently larger in diameter than the packing tube 25 to allow this to swell when the spindle, passing 30 axially through the tube, is bodily shifted upward by operation of the pressure stem 16. In operation, as soon as the tilting pressure is removed from the lever-like stem 16 the expansive, highly resilient packer tube 25 acts instantly and 35 automatically to again press the spindle 19 down and therefore brings the closure head 20 down onto its seat 21.

30 The degree of axial compression of the packing tube 25 is constantly enough to seal the spindle in the bearing 10 against leak. The parts constituting in removable insides of the faucet, and including the bearing 10 and the valve head operating tube 25, can be readily and quickly removed at will by simply screwing off the barrel boot 7. The stem and the spindle can be dismounted by first removing the valve head or closure 20, after the insides have been taken from the valve body.

40 45 What is claimed is:

50 1. A glass filler faucet including a main body having a supply chamber and a discharge spout, a cross-wall dividing the chamber from the spout, an elongated tubular bearing whose top end is shouldered and countersunk in said cross-wall and opens into said chamber and has discharge

ports to the spout, a barrel part rigid with and perpendicular to said body and in which said bearing is removably mounted, a boot screwed on the barrel and jamming the bearing to seat on said cross-wall, a valve spindle slidably fitted in the barrel and having a closure on its top end, to seal on the top of the bearing to stop fluid flow to the spout, a button on the lower end of the spindle and spaced below and adjacent to the lower end of the bearing, an elastic, expansive tube telescoped in the bearing and confined therein against said button and operative on the spindle to pull said closure to its closing position, and a tilttable lever having a part journaled in said boot and having an effective cam face spaced slightly below and operatively engageable with the button whereby to force the spindle upward and open said closure.

2. The faucet of claim 1; and the lower end of the bearing having a flared bore to provide

for relative expansion of the said tube under action of the said lever.
